UNITED STATES PATENT OFFICE.

CHARLES D. MELTON, OF EUSTACE, TEXAS.

PRESS.

Application filed February 25, 1922. Serial No. 539,271.

To all whom it may concern:

Be it known that I, CHARLES D. MELTON, a citizen of the United States, and a resident of Eustace, in the county of Henderson and State of Texas, have invented certain new and useful Improvements in Presses, of which the following is a specification.

The present invention relates in general to presses, and more particularly to a hay press or baler.

The object of the invention is to provide an apparatus of this character which is adapted to automatically and efficiently feed the material into the baling chamber in a manner to permit of continuous operation, which rapidly forms the bale and in which the feeding and baling operations are accurately timed and occur in rapid and continuous sequence.

Another object is to provide a hay press or baler embodying a plurality of swinging hoppers or bale box sections adapted to be successively loaded and swung into and out of alignment with the press box.

Another object is to provide an apparatus of this character which may be operated by horse power, or from a gasoline engine or any other suitable type of power plant, and which is of simple and durable construction, reliable in operation and easy and inexpensive to manufacture.

Other objects and advantages of the invention reside in certain novel features of construction, combination and arrangement of parts which will be hereinafter more fully described and particularly pointed out in the appended claims, reference being had to the accompanying drawings forming part of this specification, and in which:

Figure 1 is a side elevational view of the apparatus embodying the present invention;

Figure 2 is a fragmentary view in vertical longitudinal section of the baling chamber and associated parts, taken on line 2-2 of Figure 2;

Figure 3 is a view in transverse vertical section, taken approximately on line 3-3 of Figure 2;

Figure 4 is a similar view, taken on line 4-4 of Figure 2;

Figure 5 is a fragmentary view in side elevation of the press end of the apparatus;

Figure 6 is a similar view of the power end of the apparatus;

Figure 7 is a fragmentary perspective of

the power end of the apparatus, parts being disassembled for the sake of illustration;

Figure 8 is a detail view in vertical section of certain of the driven elements of the power apparatus, parts being shown in elevation for the sake of illustration;

Figure 9 is a detail perspective view illustrating, detached from the machine, the mechanism employed for actuating the feeding devices and the bale box sections;

Figure 10 is a detail perspective view of the plunger;

Figure 11 is a detail view in transverse vertical section, illustrating the signalling means of the compression chamber;

Figure 12 is a fragmentary perspective view of the signalling means detached from the compression chamber;

Figure 13 is a detail perspective view of the division block and actuator for the signalling means;

Figure 14 is a detail perspective view of a movable bale box section and its locking mechanism; and

Figure 15 is a detail perspective view of the tamper.

Referring to the drawings wherein for the sake of illustration is shown the preferred embodiment of the invention, the numeral 10 designates the body portion or reach mounted on one end upon ground wheels 11 and mounted at its other end upon steering ground wheels 12 having a tongue 13 connected thereto and being pivotally mounted with respect to the body portion of the frame.

Bars or standards 15 and 16 are carried by the body portion, the members of the pairs being disposed upon the opposite sides of the body portion, and the pairs themselves being spaced longitudinally on the body portion from each other. Transversely extending sills 17 and 18 are secured to the underside of the body portion and project beyond the sides thereof, the sills being connected with cross beams 19 and 20, arranged above the sills by means of uprights 21 and 22. Both the sills 17 and 18 and the cross beams 19 and 20 are connected with the standards 15 and 16. Adjacent the upper end of the standards cross pieces 23 and 24 are arranged and are connected thereto to complete the framework of the bail or press end of the apparatus.

A baling or compressing chamber 30 is provided, being made up of longitudinal

- pieces 31, 32 and 33 superposed on each other in edge to edge relation and suitably secured to the framework. These pieces extend rearwardly of the framework and coact with the tension device 35 at the delivery end of the compression chamber, uprights 36 being included in the tension device. The body portion or reach is provided on its underside with a plurality of cross bars 37.
- 10 A plurality, preferably a pair, of pivoted hoppers or bale box sections, designated at 40 and 41, is provided and is adapted to be successively brought into position over the baling chamber in complementary relation thereto. The hoppers 40 and 41 are pivotally connected to the opposite sides of the bale chamber 30, the section 40 being secured to one side by means of a hinge 42, and the bale section 41 being connected at 20 the opposite side by means of a hinge 43. When one of the hoppers is superposed on the baling chamber to feed its material thereto and to otherwise complement the same, the other hopper is swung outwardly 25 away from the baling chamber, with its center line substantially at right angles to the center line of the baling chamber. Platforms 46 and 47 are mounted upon the cross beams 19 and 20 and uprights 21 and 22 30 and serve to receive the hoppers 40 and 41 respectively when the hoppers are swung outwardly away from the baling chamber. Feed chutes 48 and 49 are associated with the platforms 46 and 47.
- 35 Locking mechanisms are provided for releasably securing the bale sections in position when superposed on the baling chamber in complementary relation with respect thereto. Two such locking mechanisms are 40 carried by each section and as they are identical in construction, a common description will serve for all. Each includes a latch 50 pivoted to the end walls of the hopper and connected by means of a short link 51 45 to one end of the bell crank lever 52, the other arm of which is connected to the retractile coil spring 53 which is effective to urge the latches to locking position whereby when the hopper is superposed on the 50 baling chamber the hooked end of each latch snaps over an adjacent pin 54 and 54^a provided on the framework and constituting a keeper for the latches.
- 55 A toggle is associated with each of the hoppers and each serves as a means for swinging the hopper from loading position that is from its position on the loading platform with its center line substantially at right angles to the center line of the 60 baling chamber to the position in which it is superposed on the baling chamber that is to baling position. Each toggle comprises an upper inverted U-shaped link 55 having drums 56 provided with trunnions 57 rotatably journaled in bearings 58 fixed to

the side wall of the hopper and having its body portion 59 pivotally connected with the ends of the arms 61 of the lower U-shaped link 62, the body portion 63 of which is rotatably journaled in a bearing 64 carried by the side wall of the baling chamber. The brackets 58 and the bearing 65 are so positioned and the arms of the links are of such length and are so arranged that the links are disposed in angular relation with 75 respect to each other with the lower link extending upwardly and outwardly from the baling chamber.

A crank 65 is cooperatively arranged with respect to each toggle and each includes 80 bearing portions 66 rotatably mounted in bearings provided therefor on the framework, crank arms 67 and a wiper bar 68 extending transversely of the crank arms and adapted to have wiping engagement 85 with the arms 61 with the lower link of the adjacent toggle for swinging the sections controlled by the toggle from loading position to a position complementary to the bale chamber.

A pair of upwardly extending arms 70 is carried by each crank, the arms being offset from the crank arms by means of extensions 71 formed on the wiper bar and the free ends of the arms having lateral 95 lugs 72. Links 73 are pivotally connected at their ends to the arms 70 and constrain these arms and the crank 65 to which they are connected to corresponding motion.

Flexible elements, such as chains or the like, designated at 75, are connected at one end with the lugs 72 and are connected at their opposite ends to the bell crank levers 52, the connection to these levers being such that a pull exerted by the flexible element opposes the tension of the retractile coil spring and disengages the latch from its keeper. This disengagement of the latch is the initial action incident to a pull being exerted upon the flexible element as after this initial releasing action the pull is effective to swing the hopper from baling position outwardly to loading position. It is obvious therefore that when the cranks 67 are swung outwardly they exert a pull upon the flexible element by means of the arms 70 to effect this action and when the cranks are swung inwardly the wiper bars 68 have wiping engagement with the arms 61 of the lower link 62 of the toggle to swing the hopper upwardly from loading to baling position. As the cranks 65 are constrained to corresponding motion, one of the cranks is exerting a pull by means of the arm 70 upon its flexible element when the other is 120 coacting with the toggle whereby one hopper is shifted from baling position into loading position and the other section is shifted from loading position into baling position. It is to be noted that the hopper in baling 130

position is first shifted into loading position and immediately thereafter the hopper in loading position is shifted into baling position, the flexible elements 75 and arms 5 70 acting before the cranks 65 to effect this sequence.

A trumper, designated generally at 80 is mounted upon the framework and includes a head 81 carried at the lower end of a rod 10 82 slidably mounted in a bearing provided therefor in guide bars 84 and 85. A cross head 86 is arranged at the upper end of the rod 82, and guide rods 87 are connected at one end to said cross head and at the 15 other end to the trumper head and operate in guide openings 88 and 89 provided therefor in the guide bars 84 and 85.

A walking beam 90 is provided and has rollers 91 operating in a channel iron 92 20 constituting a guideway and has its yoke end connected by means of connecting rods 93 with the trumper head and the other end pivotally supported on carrier rods 94 by means of the pivotal connections 95, the 25 rods 94 being bifurcated at their opposite ends and the bifurcated ends being pivotally connected to cross bolts 96 carried by the uprights 36.

A shaft 98 is rotatably mounted in bearings 99 carried upon the uprights 21 and 30 22 and has a crank arm 99 at one end pivotally connected to one end of an angled connecting rod 100, the opposite end of which is pivotally connected to the walking beam 35 90. Crank arms 99 coact with the stop element 101 which extends laterally from a bumper plate 102 carried by the top of the compression chamber and serving to receive the impacts incident to the movement of the 40 walking beam. When the crank arm 99 engages the stop element 101 it has moved to such position that the weight of the trumper and the walking beam is effective to exert an outward thrust upon the crank arm to 45 lock the crank arm, walking beam and trumper head in elevated position.

Spring pressed or pivoted stops or checks 102 are associated with the baling chamber and each includes a pivoted body portion 50 103 operating between the longitudinal body piece and actuated by springs 104.

A plunger, designated generally at 105 is operatively mounted in the compression chamber. The plunger (see Fig. 10) includes a plunger head comprising a head plate 106, a base plate 107 and a top plate 108 interconnected with each other and braced by means of vertical straps 109 and a transverse strap 110. A plunger rod 112 is pivotally connected to the plunger by means of a pivot bolt 113. Superposed blocks 114 and 115 arranged on the plunger and carrying an inverted stirrup 116 presenting a flat bearing surface 117. A metallic 60 apron 118 has a stationary section 119

rigidly secured to the top plate of the plunger and has a swinging section 120 hingedly connected, as at 121, to the stationary section and limited in its downwardly swinging movement by engagement with the 70 flat bearing surface of the stirrup 116. The plunger rod extends longitudinally of the frame or body portion to the power end of the press.

At the power end of the press a bed plate 75 125 is fixed to the reach or body portion 10 and a power block 130 is rotatably mounted upon a post 131 upstanding from the bed plate 125, the base of the block resting upon a circular bearing plate 132 to slightly space 80 the power block from the bed plate. A driven disk 133 is fixed to the upper end of the power block and may be driven by horse power by means of sweeps 134 or may be driven from a motor by means of suitable 85 gearing 135. The power block carries a main driving arm 136 which includes a metallic casing 137 having a roller 137^a journaled in the outer end thereof, and at a diametrically opposite point the power 90 block is provided with a second driving arm 138. The casing 137 and roller 137^a are preferably detachable. The main driving arm 136 directly engages the adjacent end of the plunger rod and imparts to the 95 plunger rod its compression movement, the plunger rod being constrained to partake of this movement by means of its pivotal connection with a crank arm 140 which is pivotally mounted upon the bed plate. The second drive arm 138 effects the return movement of the plunger rod by means of its engagement with the arm 142 of a bell crank lever 143, the other arm 144 of which is connected by means of a rod 145 with the crank 140. It is obvious that the second drive arm may be provided with a casing and roller, identical with the casing 137 and roller 137^a, so that it will also engage the plunger rod whereby the plunger 100 is given a double stroke.

The mechanism described in the preceding paragraph constitutes drive mechanism for the plunger and organized with this drive mechanism is other drive mechanism 115 for the shifting mechanism of the feed hoppers and actuating means or drive mechanism for the operating mechanism of the trumper as will be presently described.

The shifting mechanism for the hoppers and the actuating means or drive mechanism for the trumper includes a pair of posts or vertical shafts 150 and 151 upstanding from the bed plate 125 and which in the assembly are braced by a top plate 125 152 placed on the post after the other elements have been assembled thereon. As the motion of the shaft 150 is utilized to actuate the shifting mechanism it will be termed the shifting shaft, and as the mo 130

tion of the shaft 151 is utilized to operate the tramper it will be termed the tramper shaft.

The feed hoppers are shifted twice for each compression stroke of the plunger and in order to effect this shifting action the shaft 150 has fixed thereon at its lower end a sleeve 153 having an arm 154 extending laterally therefrom and connected by a connecting rod 155 with a crank arm 156 of an oscillating shaft 157 journaled in bearings 158 and connected with one of the cranks 65 for imparting the character of motion thereto necessary to effect shifting of the feed hoppers. On the upper end of the shaft 150 a second sleeve 159 is fixed and carries a shifting toe 160 which extends laterally therefrom and which is engaged by the wiping cam or arm 161 on the power block to effect the shifting of the feed hopper 40 from loading to baling position and the feed hopper 41 from baling to loading position. A sleeve 162 is rotatably mounted on the upper end of the shaft 151 and carries a shifting toe 163 extending laterally from the sleeve 162 and adapted to be engaged by a wiping cam or arm 164. The shifting toe 163 operates in a lower plane than the shifting toe 160 and consequently the wiping cam 164 is lower than the wiping cam 61, these wiping cams being also diametrically opposite. The motion which is imparted to the sleeve 162 when the wiping cam 164 engages the shifting toe 163 is transmitted reversed to the shaft 150 and from the shaft 150 it is imparted to the crank 65 to shift the feed hopper 41 to baling position and the feed hopper 40 to loading position by the motion transmission mechanism constituted by the arm 154, connecting rod 155, crank arm 156 and shaft 157. The means for transmitting the motion of the sleeve 162 to the shaft 150 and for reversing this motion includes an arm 165 extending from the sleeve 162 and an arm 166 extending from the sleeve 159 in a direction opposite with respect to the arm 165, the arms 165 and 166 being connected by a cross rod or obliquely extending connecting rod 167.

After each loaded feed hopper has been shifted from loading to baling position, the tramper descends to feed the material from the feed hopper into the baling chamber and then is returned to elevated position that is the tramper partakes once of the cycle of operation after each shifting of the feed hoppers. The drive mechanism for the tramper includes a fixed sleeve 168 keyed or otherwise secured to the shaft 151 and having a toe 169 carried thereby and extending laterally therefrom so as to be engaged by the driving arms 136 and 138. A loose sleeve 170 is arranged on the shaft 151 above the fixed sleeve 168 and carries a toe 171 engageable with diametrically opposite wiping cams or arms 172 carried by the power block 130. When the toe 171 is engaged by either of the wiping cams 172 the sleeve 170 is turned and its motion is reversed and imparted to the shaft 151 by means of a reversing element 173 loosely mounted on the shaft 150 and having arms 174 and 175, the arm 174 being connected with an arm 176^a on a disk 176 fixed on the shaft 151 by a link 177 and the arm 175 being connected with an arm 198 on the fixed sleeve 168 by means of a link 179. Motion transmission means is provided for transmitting the motion of the shaft 151 to the shaft 98 of the tramper operating mechanism and includes a drive arm 180 fixed to the shaft 151 and pivotally connected with a connecting rod 181 which extends to a crank arm 182 formed on one end of a shaft 183 journaled in bearings 184 and having a crank arm 185 connected with a link 186 which also is connected with a crank arm 187 provided on the shaft 98. When one of the driving arms engage the toe 169 the tramper is caused to descend and when one of the wiping cams 172 engages the toe 171 the tramper is caused to ascend or return to elevated position.

As the wiping cams or arms 161 and 164 coact with the wiping toes 160 and 162 to impart motion to the shifting shaft 150 these wiping cams or arms as well as these wiping toes will be hereinafter designated as shifting cams and shifting toes respectively. Similarly the wiping cams 172 and the wiping toes 169 and 171 will be termed tramper cams and toes, respectively, since these cams and toes coact to impart movement to the tramper shaft 165.

In operation the power block 130 is rotated in a counterclockwise direction as viewed in Figure 7, either by horse power when the sweeps are attached or by the gearing 135 when the motor is used.

Assuming that a charge of material has been fed into the baling chamber, the next event in the cycle of the operation will be the compression movement of the plunger which is brought about by the engagement of the driving arm 136 with the end of the plunger rod. When the plunger has completed its compression stroke the second driving arm 138 engages the bell crank 142 to effect return movement of the plunger and the wiping cam 164 to shift the hopper 41 from baling position to loading position and to shift the hopper 40 from loading position to baling position. This shifting of the feed hoppers is brought about since the movement of the shifting toe 160 turns the shaft 150 in one direction and since this movement of the shaft is transmitted to the crank 65 through the motion transmission mechanism above described, the flexible elements serving to throw the hopper 41 to loading position and the wiping bar of

one of the cranks 35 coacting with the toggle of the hopper 40 to move this hopper to baling position. After the loaded hopper has been swung to baling position the main driving arm 136 engages the toe 169 to turn the shaft 151 and through the drive arm 180 and the other elements of the motion transmission mechanism provided between the shaft 151 and the shaft 98 to turn the shaft 98 so as to swing the crank 99 thereof downwardly to cause the downward movement of the walking beam 90 and consequent descent of the trumper. The descent of the trumper feeds the material from the feed hopper into the baling chamber. Immediately after the trumper descends it is lifted or returned by the engagement of one of the arms 172 with the toe 171 which reversely moves the shaft 50 to reversely move the shaft 98 to swing the crank 99 thereof upwardly causing the walking beam to be elevated and the trumper to be correspondingly elevated. By this time the feed hopper 41 has been loaded and the next event in the cycle operations is the second shifting of the feed hoppers so as to bring the feed hopper 41, now loaded, into baling position. This second shifting of the feed hoppers is brought about by the engagement of the wiping cam 164 with the shifting toe 163, this action rotates the sleeve 162 on the shaft 151 and through the arm 165, link 167 and arm 166 turns the shaft 150 in a direction opposite to that in which it is turned in the first shifting operation so that the feed hoppers are reversely shifted that is to say that the feed hopper 41 is shifted from loaded to baling position and the feed hopper 40 is shifted from baling to loading position. This second shifting of the feed hoppers is followed by a second operation of the trumper which is effected in precisely the same manner as the first operation thereof and following this second operation of the trumper, the main driving arm 136 again engages the end of the plunger rod to actuate it through its compression stroke. This cycle of the operation is continuous and may be carried on indefinitely. It is only necessary that operators be stationed to successively load the feed hoppers.

If it desired to use a double stroke to form the bail this may be accomplished by simply attaching the casing and roller to the driving arm 138 as has been herein above fully described. If this is done both the driving arms 136 and 138 engage the plunger rod to effect two compression strokes thereof during each cycle of operation. When the motor and gearing 135 is utilized to drive the power block the post 131 is suitably braced by means of a brace bar B which is connected to the spindle of the gearing 35 and to the post.

I claim:

1. In an apparatus of the character described, a baling chamber, a plunger operating in said baling chamber, a plurality of feed hoppers movable into baling position over said baling chamber and into loading position away from said baling chamber, shifting mechanism for said hoppers, a trumper cooperable with said feed hoppers in baling position for feeding the material from said hoppers into said baling chamber, operating mechanism for said trumper, a rotatable power block having driving arms, a pair of shifting cams spaced from the driving arms and a pair of trumper cams spaced from the shifting cams and from the driving arms, one of said driving arms being cooperable with the plunger to actuate the same, a pair of shafts including a shifting shaft and a trumper shaft, a pair of shifting toes associated with the shafts and adapted to be engaged by the shifting cams to successively rotate the shifting shaft in opposite directions, motion transmission means between said shifting shaft and the shifting mechanism for said feed hoppers, a pair of trumper toes associated with the trumper shafts and adapted to be engaged by the driving arms and the trumper cams for driving said trumper shaft successively in opposite directions and motion transmission means between said trumper shaft and the operating mechanism for the trumper.

2. In an apparatus of the character described, a baling chamber, a plurality of feed hoppers movable into baling position over said baling chamber and into loading position away from said baling chamber, shifting mechanism for said hoppers, a shifting mechanism for said feed hoppers, in baling position for feeding the material from said hoppers into said baling chamber, operating mechanism for said trumper, a rotatable power block having driving arms, a pair of shifting cams spaced from the driving arms and a pair of trumper cams spaced from the shifting cams and from the driving arms, a pair of shafts including a shifting shaft and a trumper shaft, a pair of shifting toes associated with the shafts and adapted to be engaged by the shifting cams to successively rotate the shifting shaft in opposite directions, motion transmission means between said shifting shaft and the shifting mechanism for said feed hoppers, a pair of trumper toes associated with the trumper shafts and adapted to be engaged by the driving arms and the trumper cams for driving said trumper shaft successively in opposite directions and motion transmission means between said trumper shaft and the operating mechanism for the trumper.

3. In an apparatus of the character described, a baling chamber, a plurality of

- feed hoppers movable into baling position over said baling chamber and into loading position away from said baling chamber, shifting mechanism for said hoppers, a rotatable power block having shifting cams, a pair of shafts including a shifting shaft and a pair of shifting toes associated with said shaft and adapted to be engaged by the shifting cams of the power block for successively moving said shifting shaft in opposite directions, and motion transmission means between said shifting shaft and said shifting mechanism.
4. In a baling press, a baling chamber, a trumper for feeding the material into said baling chamber, operating mechanism for the trumper, drive mechanism for said operating mechanism including a rotating power block having a driving arm and a wiping cam, a vertical shaft, a fixed sleeve keyed to said shaft, a toe carried by said fixed sleeve and cooperable with said driving arm, a loose sleeve on said shaft, a toe carried by said loose sleeve and cooperable with said wiping cam, means for transmitting and reversing the motion from said loose sleeve to said shaft and motion transmission means between said shaft and said operating mechanism.
- 30 5. A baling press including a baling chamber, a plurality of hoppers pivotally mounted on said baling chamber and adapted to be successively disposed in baling position over said baling chamber and in loading position away from said baling chamber, locking mechanism for releasably maintaining said hoppers in baling position, operating mechanism for said hoppers including toggles, cranks having wiper bars coacting with said toggles, and means for constraining said cranks to corresponding movement, and means actuated by said operating mechanism for releasing said locking mechanism prior to the movement of the hopper from baling to loading position.
6. A baling press including a baling chamber, a hopper pivotally mounted on said baling chamber and adapted to be superposed on said baling chamber in baling position and to be swung away from said chamber to loading position, means for swinging said hopper from loading position to baling position including a toggle, and a crank having a wiper bar coacting with the toggle and means for swinging said hopper from baling to loading position including an arm carried by said crank and a chain connected with said arm and said hopper.
7. A baling press including a baling chamber and a hopper pivotally mounted on said baling chamber and adapted to be superposed on said baling chamber in baling position and to be swung away from
- said chamber to loading position, locking mechanism for releasably maintaining said hopper in baling position, means for swinging said hopper from loading position to baling position including a toggle, and a crank having a wiper for coacting with said toggle, and means for swinging said hopper from baling to loading position.
8. A baling press including a baling chamber and a hopper pivotally mounted on said baling chamber and adapted to be superposed on said baling chamber in baling position or to be swung away from said chamber to loading position.
9. A baling press including a baling chamber, a plurality of pivoted hoppers cooperatively arranged with respect to said baling chamber and adapted to be successively superposed on said baling chamber and locking mechanism associated with each of said hoppers including pivoted latch springs for urging said latches to latching position and keepers for said latches.
10. A baling press including a baling chamber, a plurality of hoppers pivotally mounted on the baling chamber and adapted to be successively disposed in baling position over said baling chamber and in loading position away from said baling chamber, locking mechanism for releasably mounting said hopper in baling position and operating mechanism for said hoppers including a toggle pivoted to each of said hoppers, cranks having wiper bars coacting with said toggles for urging said hopper from loading to baling position, means for constraining the cranks to corresponding movement including arms carried by the cranks and links connecting the arms, and flexible elements connecting the arms and the hoppers and adapted to shift the hoppers from baling to loading position prior to the action of the toggles.
11. In an apparatus of the character described, a baling chamber, a pair of feed hoppers movable into baling position aligned with the baling chamber and into loading position away from said baling chamber, a trumper cooperable with the feed hopper aligned with the baling chamber for feeding the material into the baling chamber and driving mechanism for the trumper, a plunger cooperable with the baling chamber for forming the bale, and driving mechanism for the plunger.
12. In an apparatus of the character described, a baling chamber, a pair of feed hoppers movable into alignment with the baling chamber and out of alignment therewith, and means for moving said hoppers including a toggle associated with each of said hoppers, and a crank each of said toggles having a wiping bar engageable with one of the links of each of said toggles.
13. In an apparatus of the character de-

- scribed, a baling chamber, a trumper for feeding the material into the baling chamber, operating mechanism for the trumper including a walking beam, a guideway for said walking beam, rollers carried by the walking beam and cooperable therewith, connecting rods between the walking beam and the trumper and drive mechanism for the operating mechanism.
- 10 14. In an apparatus of the character described, a baling chamber, a pair of feed hoppers, means for successively shifting said feed hoppers into baling and loading position with respect to said baling chamber, a trumper cooperable with said feed hoppers for feeding a charge of material into the baling chamber, means for operating said trumper after each shifting of said feed hoppers, a plunger cooperable with the baling chamber, and means for imparting compression stroke to the plunger subsequent to the charging of the baling chamber.
- 15 15. In a baling press, a baling chamber, a plunger operating in said baling chamber, a hopper movable into baling position on said baling chamber or loading position away from said baling chamber, said hopper being open at its ends to permit of loading of the hopper and to permit the charging 20 of the baling chamber from the hopper, and a trumper cooperable with the hopper in baling position and arranged to descend down through the upper open end of the hopper and through the bottom thereof to feed the material through the lower open end of the hopper into said baling chamber.
- 25 16. In a baling press, a baling chamber and a plunger operating therein and comprising a plunger and including a head plate, a base plate and a top plate interconnected, and straps bracing said plates, a plunger rod, a pivot bolt connecting said plunger rod and said plunger head, superposed blocks on said plunger rods, an inverted stirrup associated with said blocks 30 and said plunger rod, and an apron including a stationary section secured to the top plate of the head and a swinging section engageable with the stirrup.
- 35 17. A baling press including a baling chamber, a plurality of hoppers pivotally mounted on said baling chamber and adapted to be successively disposed in baling position over said baling chamber and in loading position away from said baling chamber, the ends of the hoppers being open, the lower ends of the hopper communicating with the baling chamber when the hoppers are disposed in baling position and the upper ends constituting the outer ends of the 40 hopper in loading position and presenting the openings into which material is fed.

CHARLES D. MELTON.
